UNITED STATES PATENT OFFICE.

JOHN HENRY HECKER, OF COVINGTON, OHIO.

DISPENSING APPARATUS FOR AUTOMOBILE SERVICE.

1,379,562.

Specification of Letters Patent. Patented May 24, 1921.

Application filed September 2, 1920. Serial No. 407,717.

To all whom it may concern:

Be it known that I, JOHN HENRY HECKER, a citizen of the United States, residing at Covington, in the county of Miami and State of Ohio, have invented certain new and useful Improvements in Dispensing Apparatus for Automobile Service, of which the following is a specification.

This invention relates to service stand equipment for automobiles and pertains especially to a stand having a plurality of dispensing equipment operated independently at various distances from an automobile for supplying such necessities as air, water and electric light.

The object of the invention is to provide a service stand for dispensing water, air, etc., for automobiles and having such construction and arrangement of parts as to afford independent assembly of a plurality of casings and to provide each casing with an independent loose gravity pulley or sheave for retracting extensible conveyer pipes and an electric light wire.

A further object of the invention is to provide special pipe connections between the extensible pipes or hose and their supply pipes, and to furnish a pulley or sheave of special construction without retracting springs and separate weights, and having free vertical movement for permitting extension of the hose and the retraction thereof in a dispensing operation.

Various other objects, advantages and improved results are attainable in the production and practical utility of the invention, as will be hereinafter fully disclosed.

In the accompanying drawings forming part of this application:—

Figure 1 is a perspective view showing the service elements retracted and in position to be withdrawn for application to an automobile.

Fig. 2 is a vertical sectional view taken on the dotted line 2—2 Fig. 3.

Fig. 3 is a vertical sectional view taken on the dotted line 3—3 Fig. 2.

Fig. 4 is a cross section taken on the dotted line 4—4 Fig. 3.

Fig. 5 is a detail sectional view of one of the gravity sheaves.

The same reference characters denote the

same parts throughout the several views of the drawings.

In carrying out my invention, I employ a suitable base as 1, having sub-base elevations 2, and a binding cap or cover 3 having similar projections 4. The cap or cover 3 has an electric light fixture 5 provided with a globe 6. The elevations 2 and the projections 4 are located opposite each other in the same vertical plane, so that the said members 2 and 4 form three pair of holding devices fitting within the casings, hereinafter particularly referred to.

The casings as 7, 8 and 9 are of the same construction, being formed of thin metal the side edges of which are bent into corner folds 10 forming vertical braces, and the front of each casing is provided with a hood 11 overhanging an opening or mouth 12, said hoods being preferably struck out of the sheet metal forming the casings. The top and the bottom of the casings fit over the base members 4 and the cap members 2, respectively, and are secured thereto by suitable screws 13. The casings 7, 8 and 9 have sheaves or pulleys as 14, journaled in the upper portion thereof and opposite the mouth 12 by means of a shaft 15, and these sheaves or pulleys will be hereinafter referred to as the shaft sheaves. The shaft 15 is arranged to be withdrawn for removing and remounting one or more of these sheaves as desired or as occasion may demand, and forms an expeditious means for assembling these parts. Each casing is also provided with a loose gravity sheave 16, hereinafter to be more particularly described. A water supply pipe 17 extends through the base 1 and projects upwardly into the casing 7 and is provided with a coupling 18 having a suitable hand valve 19 upon the outside of this casing. A water tube 20 extends upwardly from the coupling 18 and has a depending discharge end 21 to which one end of a water hose 22 is attached. The hose 22 extends under the loose sheave 16, over the shaft sheave 14 of this casing and through the mouth 12, and the free end of the hose 22 has coupled thereto a curved discharge pipe 23. A similar arrangement is made for supplying air through the casing 8, by an air supply pipe 24 having a hose 25 extend-

ing under the sheave 16, and over the shaft sheave and connected with said pipe and with a hand valve 26 by a coupling 27. A pressure gage 8^a is connected with the air pipe 24. The free end of this hose extends through the mouth of the casing 8 and is provided with a coupling 28. The electric light wires or cable 29 is introduced into the casing 9 by means of a conduit pipe 30. 5 The wires are connected as at 31 with a switch button 32 on the front of the casing 9, and after extending the cable under the loose sheave and over the shaft sheave of this casing, the free end of the cable depends 10 from the mouth of this casing and is provided with an electric lamp 33 having the usual guard or cage 34. This lamp may be withdrawn to a distance and to various positions for inspecting and repairing an 15 automobile and when released it is retracted by its gravity sheave to its place for future use.

Referring to the loose or gravity sheave, as particularly shown in Fig. 5 of the drawings, the shell members 35 are provided with 20 disk weights 36 secured together by means of bolts 37 and forming a central bearing of solid metal body for the hose and cable hereinbefore mentioned. Obviously these weights 25 are sufficient to overcome the weight of the hose and cable and their attachments when the base and cable are released, after having been withdrawn, and the gravity sheaves will retract the hose and cable to the positions as shown in Figs. 1 and 3 of the drawings. 30

It will be seen that the casings are independently arranged so that one may be removed and replaced without removing the others, that the gravity sheaves fit within 40 the casings so as to have the annular flange of these sheaves make a parallel bearing on the inner face of the casings whereby these sheaves rise and fall centrally under the shaft sheaves, that by reason of the 45 relation of the sheaves to the casings the hose and cable are prevented from wedging between the sheaves and the side walls of the casing, that the annular flange of all the sheaves are in such close proximity to the 50 rear wall of the casings as to prevent dislodgment of the hose and cable from the sheaves, and that the hoods not only form a cover for the mouth of the casings but form an overhanging roof for the valves 55 and the electric button.

Obviously the gravity sheaves being independently loose, one is free to move vertically during its revoluble movement of the other gravity sheaves, and that the gravity 60 sheaves may be afforded a greater field of vertical movement by increasing the height of the casings and thereby afford the use of longer hose and cable.

I do not wish to be understood as confin-

ing the invention to material, size and shape 65 nor to the number of cells or casings, as these may be increased in number for certain other service supply elements, but reserve the right to make such changes and variations in the manufacture and practical 70 application of the invention as may not be inconsistent with the appended claims.

Having thus described my invention what I claim as new and desire to secure by Letters Patent is:—

75

1. In a dispensing apparatus of the character described, a plurality of separate casings, a base and cover common to all of the casings and permitting independent removal and replacing of the casings, a shaft 80 extending through the casings, a sheave in each casing and mounted on the shaft, a gravity sheave loosely contained in each casing, said gravity sheaves having independent vertical movement with respect to 85 each other and with respect to said shaft sheaves, a dispensing conveyer for each casing and working under the gravity sheaves and over the shaft sheaves for extension and retraction, and controlling means upon the 90 outside of the casings to which said conveyers are attached.

2. In an apparatus of the character described, a plurality of independent casings having open ends, a cap having projections 95 fitting and closing one end of each of the casings, a base having elevations corresponding with said projections and fitting and closing the other end of each of the casings, said casings being separately mounted in 100 vertical parallel position, and means for securing the casings to the cap and to the base.

3. In an apparatus of the character described, a plurality of assembled separated casings, a binding cap and a base for the 105 casings, a shaft extending through the casings, sheaves revoluble in the casings on the shaft, gravity sheaves loose within the casings, and dispensing conductors connected with a source of supply through said base 110 and having the gravity sheaves riding thereon, all of said sheaves fitting the casings so as to prevent dislodgment of the conductors.

4. In an apparatus of the character described, a plurality of independent casings, a binding cap having projections fitting the upper end of the casings and forming a cover, a base having elevations closing the bottom of the casings, a source of supply 115 pipe extending through the base and projecting therefrom vertically into certain of the casings, a coupling having a valve stem extending through the front of said certain casings, dispensing pipes extending vertically from said couplings, dispensing hose attached to said dispensing pipes, sheaves journaled in said casings, and gravity 120 125

sheaves adapted to ride loosely on the hose and to be guided in vertical movement by the inner face of the casings.

5. In an apparatus of the character described, a plurality of independent casings, a removable cap covering all the casings, a base common to all the casings, and cap and base members fitting within the casings for

holding the casings spaced apart in vertical parallel position. ¹⁰

In witness whereof I hereunto set my hand in the presence of two witnesses.

JOHN HENRY HECKER.
